CABLE CONNECTER

William A. Bonnell, New York, N. Y.

Application January 27, 1931, Serial No. 511,515

3 Claims. (Cl. 247—25)

This invention relates to cable connectors for use in joining cables to electric box fixtures such as outlet boxes, cable boxes, switch boxes and the like.

5 An object of my invention is to provide an improved cable connector of simple and rugged construction, having novel means to securely clamp a cable therein and for quickly and rigidly anchoring the cable connector in an outlet box 10 or other electrical fixture.

In carrying out my invention, I preferably utilize but two elements, namely, the connector body and a clamp pivotally positioned thereon to clamp the cable therein and anchor the connector body in the outlet box.

15 In the preferred form of my invention, the connector body is provided with a projection at its lower end, to engage the underside of the outlet box adjacent the knock-out opening in which the connector body is positioned.

20 The clamp is bent intermediate its length, the upper end being formed into a cable-clamping jaw. The clamp is further provided, adjacent the jaw with an aperture through which a screw 25 or the like, whose head bears against the clamp, and whose stem threadedly engages the connector body, loosely passes.

When the screw is threaded into the connector body, the screw head draws the clamping jaw 30 toward the connector body, thereby firmly clamping the cable in the connector body, while the lower end of the clamp, due to the bent fulcrum-like structure thereof is moved outwardly and wedges against the edge of the knock-out opening 35 in which the connector is positioned, securely anchoring the connector body in the outlet box.

This and other advantageous objects, which will 40 later appear, are accomplished by the simple and practical construction and arrangement of parts hereinafter described and exhibited in the accompanying drawing, forming part hereof, and in which:

Figure 1 represents a vertical sectional view of 45 the preferred form of my invention, in an outlet box, also shown in section, and supporting a cable shown partly in section.

Figure 2 represents a top plan view, partly in 50 section, taken on lines 2—2 of Figure 1, in the direction indicated by the arrows.

Figure 3a represents a vertical sectional view 55 taken on lines 3a—3a of Figure 2, in the direction indicated by the arrows.

Figure 3 represents a top plan view of the preferred form of my invention supporting a cable,

shown in section, and secured in an outlet box, shown fragmentarily.

Figure 4 represents a perspective view of the clamp used in the preferred form of my invention.

Figure 5 represents a side elevational view of the preferred form of my invention, showing the manner in which it is first inserted into the outlet box, shown partly in section.

Figure 6 represents a view of a modified form 10 of my invention similar to the view of the preferred form of my invention shown in Figure 1.

Figure 7 represents a top plan view of this modified form of my invention, supporting a cable, shown in section, and secured in an outlet box, 15 shown fragmentarily.

Figure 8 represents a perspective view of the clamp used in this modified form of my invention.

Figure 9 represents a top plan view partially in section of another form of my invention.

20 The preferred form of my invention, shown in Figures 1, 3, 4 and 5 consists, essentially, of but two members, namely, the connector body 1 having a bushing 21 at one end, provided with a circumferential flange 4 midway its height, a laterally extending projection 5 at a point on its circumference intermediate the flange 4, and the bushing end of the body 1 and a threaded aperture 3 at a diametrically opposite point, above the flange 4 and the clamp 2, one end of which is angularly bent and cut to provide a cable clamping jaw 6, said clamp 2 being further bent intermediate its length.

25 The clamp 2 is pivotally positioned on the connector body 1 by any suitable means, as by a screw 7 passing through an aperture 8 (see Figure 4), in the clamp 2 and threadedly engaging the threaded aperture 3 of the connector body 1.

30 In using my invention, one of the knock-outs 10 of the outlet box 11 is removed in the conventional manner, leaving a knock-out opening 12, in which the connector body 1, and clamp 2 are inserted, at an angle (see Figure 5), to bring the bevelled projection 5 of the connector body 1 into engagement with the edge of the outlet box opening 12, and the connector body 1 is then brought 35 down so that its circumferential flange 4 overlies the knock-out opening 12.

35 The head 9 of the screw 7 bears against the jaw end of the clamp 2. Therefore, on further 40 threading the screw 7 into the threaded aperture 3 of the connector body 1, the jaw end of the clamp 2 will be drawn toward the connector body 1, causing the jaw 6 of the clamp to engage with 45 and rigidly secure the cable 13 against the inner 50 55

part of the connector, the lower end of the armor 13 of the cable resting on the bushing 21 in the connector body 1. As the clamp 2 is angularly bent intermediate its length, this threading of the 5 screw 7 causes the clamp to act as a fulcrum, wedging the bushing end of the clamp against the edge of the knock-out opening 12, securely anchoring the connector body 1 therein.

In the modified form of my invention, shown 10 in Figures 6, 7 and 8, the cable clamping jaw of the clamp, consists of two parallel, spaced members 14—14, preferably formed integral with and at right angles to the clamp 2', which are adapted to pass through spaced parallel slots 15—15 in 15 the connector body 1'; in its other feature this form of my invention corresponds with the preferred form of invention.

My improved cable connector is used as follows:

The connector body 1 and clamp 2 are inserted 20 in the outlet box opening 12 at an angle (see Figure 5) so that the lateral projection 5 of the connector body 1 will be slid into the outlet box, then the connector body 1 is brought down so that its flange 4 overlies the opening 12 (see Figures 25 3 and 7), and the screw 7 is threaded into the threaded aperture 3 of the connector body 1.

The connector body 1 is rigidly secured in the outlet box by the engagement of the lateral projection 5 with the edge of the knock-out opening 30 12 and the wedging of the bushing end of the clamp 2 against the opposite edge of the opening 12 at an angle (see Figures 1, 2, 5 and 6).

To remove the cable from the connector body it is merely necessary to turn the screw 7 to draw 35 the screw head 9 away from the clamp 2. The clamp 2 may then be moved back, carrying the cable clamping jaw 6 away from the cable 13, so that the latter may be readily withdrawn.

The clamp is bent angularly, intermediate its 40 length, so that outward movement of the jaw end of the clamp 2 will cause the other end of the clamp to be drawn forward toward the connector body 1, parallel with the edge of the opening 12, as shown in dotted lines in Figure 3a, so that the connector body 1 and clamp 2 may be withdrawn 45 from the outlet box opening 12 at the angle in which they are first inserted into the said opening (see Figure 5).

It will be noted that, as the clamp 2 is made 50 preferably of flat stock and the knock-out opening 12 is circular, the edges of the clamp 2 engage the knock-out opening 12, as is clearly shown in Figures 2 and 3a, and the bent part of the clamp 2 has tangential engagement with the side of the connector body 1, as shown in Figures 1, 2 and 6.

If desired, the connector body 1 may be flattened or recessed at the point at which it is engaged by the bent part of the clamp 2 so that a wider bearing surface will be provided, and the 60 clamp 2 may be curved or otherwise bent at its lower end, to wedge against the edge of the knock-out opening 12 at different points.

In the form of my invention shown in Figure 9, the connector body 1' is provided with a vertical 65 recess 17, the lower end of which is preferably inwardly inclined, so that the clamp 2 may be held therein without completely filling the same, when the connector body 1 and clamp 2 are first inserted into the conventional knock-out opening 12'. This arrangement enables the use of standard connector bodies of a diameter slightly less than that of the knock-out opening 12', the connector bodies being provided with the vertical recess 17.

To adapt my improved cable connector for use in connection with cables of various diameters, the cable-clamping jaw 6 of the clamp 2 may be varied in length to accommodate cable of various diameters or the clamp 2 may be weakened to enable it to be drawn further forward to carry the cable-clamping jaw 6 into clamping relation with cables of various diameters, after the clamp 2 has been drawn to the position in which it has 10 wedging engagement with the edge of the knock-out opening 12. The jaw end of the clamp 2 may be weakened in any convenient manner, as by providing it with notches 16 as shown in Figure 8; or by making it of material of less thickness than that of the other end thereof.

The clamp 2 may be provided with laterally extending stops 18 (see Figures 2 and 4) to engage with the underside of the outlet box adjacent the knock-out opening 12, to prevent withdrawal of the connector body and clamp.

It will be noted that in using my improved cable connector the screw 7 does not engage the cable, so that danger of injury to the cable from this source is eliminated, and that the cable may be readily inserted in and removed from the connector body before or after the latter is inserted into the outlet box opening.

The foregoing disclosure is to be regarded as descriptive and illustrative only, and not as restrictive or limitative of the invention, of which 30 obviously an embodiment may be constructed including many modifications without departing from the general scope herein indicated and denoted in the appended claims.

Having thus described my invention, what I 35 claim as new and desire to secure by Letters Patent, is:

1. A cable connector comprising a hollow body having opposite ends and a clamp member fulcrumed to said body, said clamp member having oppositely directed ends, one of said ends being angularly disposed to provide a jaw extending over an end of the hollow body, the other end of said clamp member being angularly directed for fulcrum engagement with the edge of an outlet box opening to secure the hollow body therein.

2. A cable connector comprising a hollow body having opposite ends, said body having a threaded portion, a clamp member, and a screw freely passing through said clamp member and threadedly engaging the threaded portion of the body to secure the clamp member thereto, said clamp member having oppositely directed ends, one of said ends being angularly disposed to provide a jaw extending over an end of the hollow body, the other end of said clamp member being angularly directed for fulcrum engagement with the edge of an outlet box opening to secure the hollow body therein.

3. A cable connector comprising a hollow body having opposite ends, and a clamp member fulcrumed to said body, said clamp member having oppositely directed ends, and being provided with laterally extending stops intermediate its ends, whereby, when the cable connector is positioned in an outlet box opening with the laterally extending stops below the opening, the clamp member may be fulcrumed on the hollow body so that the laterally extending stops will be brought into engagement with the underside of the edge of the outlet box opening to secure the body therein.

WILLIAM A. BONNELL.
